W. E. BARKER.
ROTARY SPRINKLER.
APPLICATION FILED JUNE 26, 1917.

1,266,384.

Patented May 14, 1918.

UNITED STATES PATENT OFFICE.

WYNDHAM E. BARKER, OF FORTUNA, CALIFORNIA.

ROTARY SPRINKLER.

1,266,384.

Specification of Letters Patent. Patented May 14, 1918.

Application filed June 28, 1917. Serial No. 177,016.

To all whom it may concern:

Be it known that I, WYNDHAM E. BARKER, a citizen of the United States of America, residing at Fortuna, in the county of Humboldt and State of California, have invented certain new and useful Improvements in Rotary Sprinklers, of which the following is a specification.

My present invention relates to improvements in rotary sprinklers, and is designed especially for the purpose of providing a long arm sprinkler adapted for use in gardens, lawns, fields, etc., which is simple in construction and operation, comparatively cheap in first cost, durable, and efficient.

The invention consists in certain novel combinations and arrangements of parts as hereinafter set forth and claimed.

In the accompanying drawings I have illustrated one complete example of the physical embodiment of my invention constructed according to the best mode I have so far devised for the practical application of the principles of the invention and this embodiment has proven highly satisfactory in actual practice.

Figure 1 is a side elevation of a rotary sprinkler constructed and operating according to my invention.

Fig. 2 is a top plan view of the device of Fig. 1.

Fig. 3 is an enlarged, detail, sectional view of the fixed supporting head and water connections.

Fig. 4 is a top plan view of one of the nozzles.

Fig. 5 is a sectional view on line 5—5 Fig. 4.

Fig. 6 is a slightly modified form of the invention.

In the preferred embodiment of my invention as illustrated in the drawings I utilize galvanized iron pipes and similar fittings, and the device is usually supported upon a tripod or stand made up of pipe lengths, 1, 1, 1, which are threaded into a head or casting 2 formed hollow to accommodate the fixed casing or outer pipe 3. The head is fashioned with obliquely projecting bosses 4, threaded for the reception of the tripod pipes 1, and it will be seen that these pipes at their upper ends bear against the periphery of the pipe 3 and hold it rigidly in fixed position.

At its lower end below the head 2, the fixed casing 3 is externally threaded to re-

ceive the reducing socket 5, which has there-in a rubber or leather gasket or washer 6 provided with an opening of less diameter than the bore of the connecting pipes, and a coupling sleeve 7 is threaded into the reduced end of the reducing socket. The hose coupling 8 is carried by the sleeve, and if desired may be soldered to make a rigid fitting. The hose 9 is indicated as attached to the coupling and through the hose the water, under pressure, flows to the sprinkling device.

The above described parts form the stationary support and connections for the sprinkler which has a water pipe 10 with its exterior periphery turned smooth to fit neatly in the casing 3, and the water pipe is designed to revolve freely and smoothly in the casing, which latter acts as a support and guide for the rotary or revolving parts.

At its upper end the water pipe is fitted and fixed in the two-way casting 11, which has a bearing surface 12 on the smooth top edge of the fixed casing 3, and from this head the two sprinkler arms or pipe sections 13, 13 project diametrically, while the outer extensions or sections 14, 14 are threaded in the outer ends of the inner sections, and project therefrom as indicated.

Each sprinkler arm, at its backwardly and upwardly turned ends, is provided with a closed cap 15 threaded on the arm, and provided with an opening 16 cut in the edge of the cap and oblique to its longitudinal axis in order to receive the inverted U-shaped, bent, copper plate 17 which is soldered in the opening and fashioned with a slit or slot 18 to enable the cap to perform the functions of a nozzle and spray a fan-shaped emission of water as the sprinkler arms revolve.

Located at right angles to the sprinkler arms and extending diametrically are a pair of lateral brace arms 20, 20, threaded into the casting or sprinkler head 11, and wire braces 21 extend from the top of the supporting tower 19 to the sprinkler arms and brace arms as indicated, the tower consisting of a pipe threaded into the top of the casting or head 11, but of course closed against ingress of water.

In Fig. 6 a slight modification is illustrated wherein the pipe 22 is fixed in the reducing socket 5, and a T-coupling 23 is threaded on the lower end of this pipe and a pressure reducing plug 24 is adapted to

close the opening or reduce the opening from the lateral flanged sleeve 25 which is threaded into the T-coupling and has a hose coupling 26 and hose 27 attached thereto.

- 5 The water pressure is designed to be of sufficient power to lift the revolving parts of the sprinkler from close frictional contact with the upper edge of the outer casing and the washer 6, but should the water pressure 10 sure become of sufficient power to lift the revolving parts to such an extent that leaks should occur, the pressure may be controlled by adjusting the plug 24 to close the inlet of water from the hose, or regulate it as desired.
- 15

One of the meritorious features of my invention resides in the use of the long sprinkler arms by means of which a great area may be sprinkled or sprayed, and in

some instances when extremely long arms 20 are used the tripod or stand may be dispensed with and the revolving device be supported from a post or standard. It will be understood that different lengths and sizes of pipes and fittings may be used, and 25 the embodiment of my invention may be altered or changed within the scope of my claim without departing from the spirit of my invention.

What I claim is:—

The combination with a sprinkler arm of a closed end cap having an opening therein forming a nozzle oblique to its longitudinal axis, and a slotted, inverted U-shape plate fixed over said opening.

In testimony whereof I affix my signature.

WYNDHAM E. BARKER.
